UNITED STATES PATENT OFFICE.

LEWIS LILLIE, OF TROY, NEW YORK, ASSIGNOR TO JOHN W. BATES.

FIREPROOF SAFE.

Specification forming part of Letters Patent No. 8,223, dated July 15, 1851; reissued November 21, 1865, No. 2,212.

To all whom it may concern:

Be it known that I, LEWIS LILLIE, of Troy, in the county of Rensselaer and State of New York, have made certain new and useful Improvements in the Construction of Iron Safes or Bank-Vaults; and I do hereby declare that the following is a full, clear, and exact description of the same, reference being had to the annexed drawings, making 10 a part of this specification, in which—

Figure 1 is a perspective view of the safe and Fig. 2 a vertical transverse section of the same from front to back.

The nature of my invention consists in 15 constructing my safe in part of wrought and part of cast iron, which is without bolts or rivets as in the usual mode, my mode of construction being to render it more secure against burglary by rendering it secure 20 against being broke or drilled into.

The construction is as follows: I construct a wrought iron box *a*, of the desired size and thickness, which is made usually of boiler iron, through which I enter rivets *b*, *b*, extending outward; around this box I cast iron *c*, *c*, to any given thickness, that may be desired for strength and security, the effect being that the cast iron chills to a great degree of hardness and adheres to the wrought iron and is 25 firmly bound by the rivets by clenching them 30

in the casting. The wrought iron box thus forms the core for casting upon, and secures strength in toughness, in the formation, which renders it secure against being broke by any ordinary power which may be 35 brought to bear upon it. While the cast iron (which ordinarily forms the greatest bulk of the safe) being chilled, renders it secure against being drilled through, thereby rendering it burglar proof. 40

In Fig. 3 I have shown a modification of my plan of combining wrought and cast iron, which in effect will be the same as above described. Instead of the wrought plates, I employ wrought bars *d*, *d*, surrounded by cast iron (*e*, *e*), thereby rendering it secure against force and drills as 45 above described.

Having thus described the nature of my invention, what I claim as new and desire 50 to secure by Letters Patent, is—

The combination of wrought and cast iron, the same forming a safe in the manner and for the purpose substantially the same as described.

LEWIS LILLIE.
